UNITED STATES PATENT OFFICE

RALPH M. ELLIOTT, OF MINNEAPOLIS, MINNESOTA, ASSIGNOR OF ONE-FIFTH TO CHRIS W. LEE, ONE-FIFTH TO EALARD A. ARNTSON, ONE-FIFTH TO MILLARD W. RICE, AND ONE-FIFTH TO ALBERT GOETZE, ALL OF MINNEAPOLIS, MINNESOTA

CONTAINER FOR CONFECTIONERY AND OTHER GOODS

Application filed September 11, 1929. Serial No. 391,767.

This invention relates to containers for holding and displaying goods and especially to a highly ornate container for candies, confectionery and other small articles.

It is an object of my present invention to provide a simple container which may be adapted for candy, confectionery or other small articles having an attractive and ornate appearance and wherein a portion of the contents may be displayed or viewed without removing the cover of the container and without exposing the same.

More specifically it is an object to provide a container of the class above described, having in the top or other suitable portion thereof a pictorial representation of an object such as a door, window, blind or other object which has a substantially regular area, constructed from a flap of material to swing in the manner of a true closure member and exposing through a transparent sheet or pane, a portion of the contents of said container.

It is a further object to provide in a candy box or other container, structure for securing a sheet of cellophane or other transparent material to an apertured portion of the cover or other appropriate portion of the box without applying adhesive to the cellophane and without impairing the ornate appearance of the outer portion of the container.

In some containers, transparent sheets, such as cellophane have been used as a top or cover to the container and the edges of the transparent sheet have been adhesively secured to the rim or upper edge of the box. Variations in temperature and humidity conditions, because of the fact that the edges of the cellophane or transparent sheet were adhesively secured, often caused the transparent sheet to wrinkle, crack or warp out of shape.

With my structure, the cellophane or other transparent sheet material may be attached to a viewing aperture in the cover or other portion of the box and will always lie perfectly flat, presenting an ornate appearance and will never wrinkle or crack due to temperature or humidity variations.

The above stated and other objects will be fully set forth in the following description made in connection with the accompanying

drawings in which like reference characters refer to similar parts throughout the several views and in which:—

Fig. 1 shows a perspective view of an embodiment of the invention to be used for a 55 confectionery box;

Fig. 2 is a vertical section taken longitudinally through the box shown in Fig. 1, the dotted lines indicating the moved position of the closure member to permit the contents 60 of the container to be viewed;

Fig. 3 is a bottom plan view with some portions broken away of the inner side of the container cover; and

Fig. 4 is a plan view of the inner sheet of 65 the box cover, the dotted lines indicating where the edges are scored or folded to form down-turned flanges.

The embodiment of the invention illustrated in the drawings, is a confectionery or candy box although, of course, my invention is adapted for boxes and containers for various purposes. The body of the box is of common construction comprising a sheet member 5 which may be constructed of cardboard or other suitable material having the upturned side and end flanges or walls 6 and 7. A bottom sheet 8 is adhesively secured to the under side of sheet 5 and as shown is of larger area than said sheet affording a decorative flange 80 at the bottom of the box. As usual, the sheets 5 and 8 and the side and end walls 6 and 7 are externally covered with thin sheet material 10, such as paper, folded about the edges of the sheets and pasted thereto. 85

The top or cover of the box comprises a generally rectangular sheet of cardboard or other relatively stiff material 11 cut out in the manner shown in Fig. 4 to afford when folded side and end flanges 11a and 11b, 90 which portions are scored as shown by the dotted lines, to be folded downwardly constituting the overlapping edges of the cover. Sheet 11 also has a rectangular flap portion 12 cut therein and a relatively large viewing 95 aperture 13 is formed in said flap.

A top sheet 14 of slightly greater area than the area of sheet 11, when the sides and ends are folded on the dotted lines, is secured preferably by adhesive material to the upper sur- 100

face of sheet 11, the edges of sheet 14 slightly overhanging the edges of sheet 11. In the construction of the box, the flap 12 is not adhesively secured to the portion of sheet 14 directly thereabove but is adapted to be swung outwardly for the insertion of a sheet T of transparent material such as cellophane between itself and the opposing portions of sheet 14, whereafter said flap may be secured in closed position to the adjacent portion of sheet 11, as will later appear.

The box cover comprising sheets 11 and 14 is externally covered with decorative paper or other suitable sheet material 15, the covering extending over the depending flanges or walls 11a and 11b and adhesively secured to the cover and folded about the edges of said walls. On the top or outer surface of the box cover and usually printed upon the covering 15 a picture or design appears and in accordance with my invention, this design includes a well defined pictorial representation of some object, usually a closure member, such as a door or window, but, of course, other suitable objects may be pictured, such as a roof of a house, a swimming pool, a garden or any object having area, the edges of which are well defined. The sheet 14 and covering 15 are cut on a line 15a which defines the edge of the door closure member or other object pictorially represented on the box, thereby forming a flap 16, constituting the pictorial closure member or object and acting as an actual closure member for the cover of the box. Line 15a on which the covering 15 and sheet 14 are cut is usually made to coincide with the inner edge of the apertured flap 12 forming registering viewing openings in the two sheet members 14 and 11 constituting the cover of the box. The flap 16 may be swung outwardly, swinging on a line or axis 15b indicated by dotted lines in Fig. 1. Flap 16 is usually scored along line 15b to facilitate opening of the pictured closure member.

From the inside of the box cover a transparent sheet, such as cellophane, transparent celluloid or other suitable material is inserted between sheets 11 and 14 beneath flap 12 of sheet 11. The flap is then swung back to place against the transparent sheet and the free edges of the flap are secured to the adjacent edges of the sheet 11, by suitable means such as adhesive strips or tape 17. The transparent material is thus held flat, directly below the viewing apertures formed in flap 12 and sheet 14 of the cover.

Cellophane, transparent celluloid and other transparent sheet material is considerably affected by variations in temperature or humidity, and if the edges of the sheet are cemented or adhesively connected to a frame, the transparent sheet will often warp, crack or become distorted due to such variations.

With my structure, the transparent sheet is frictionally held between the edges of the flap

12 and the edges of sheet 14 about the flap 16. Thus, expansion and contraction of the transparent material will not impair its quality or appearance.

It will be seen from the foregoing description that my container presents an attractive and novel appearance and permits a portion of the contents of the container to be conveniently viewed by swinging out the flap 16, constituting the closure member. The contents of the container are protected from dust and moisture whether the flap 16 is opened or closed and the combination including the flap or closure member for the cover, pictorially representing an object, such as a door or window or other real object is thought novel.

It will be seen that my structure may be manufactured at comparatively low cost and constitutes a novel, ornate and highly efficient container, adapted for holding and displaying goods.

It will, of course, be understood that various changes may be made in the form, details, arrangement and proportions of the parts without departing from the scope of applicant's invention.

What is claimed is:

1. In a container, a wall constructed of inner and outer sheets of material secured together, said outer sheet having a flap cut therein to form a closure member, said inner sheet also having a flap cut therein of somewhat larger area than said first mentioned flap, said last mentioned flap having an aperture therein substantially in registration with the aperture formed by said first flap, a sheet of transparent material inserted between said last mentioned flap and said outer sheet and covering the area of said first mentioned flap, and means for securing said last mentioned flap in closed position to the adjacent portions of said inner sheet.

2. The structure set forth in claim 1, wherein said means comprises a strip of adhesive flexible material overlapping a portion of the free edge of said flap and an adjacent portion of the inner sheet of material.

3. In a container a wall constructed of inner and outer sheets of material, said outer sheet having a flap cut therein to form a closure member, said inner sheet also having a flap cut therein of somewhat larger area than said first mentioned flap, said last mentioned flap having an aperture therein, said aperture being exposed by the aperture formed by said first mentioned flap and a sheet of transparent material inserted between said last mentioned flap and said outer sheet and covering the area of said first mentioned flap.

4. In a decorative container a wall constructed of inner and outer sheets of material secured together, said outer sheet having a flap cut therein to form a swingable closure member, said inner sheet having an

aperture therein, said aperture lying within
the area of said flap, a sheet of transparent
material inserted between said sheets and
covering the area of said flap, said inner sheet
5 being slit adjacent said aperture to permit
insertion of said transparent sheet.

In testimony whereof I affix my signature.
RALPH M. ELLIOTT.
